UNITED STATES PATENT OFFICE.

PHILIP B. BRILL, OF BRIDGEPORT, CONNECTICUT, ASSIGNOR TO THE LAKE TORPEDO BOAT COMPANY OF MAINE, OF BRIDGEPORT, CONNECTICUT, A CORPORATION OF MAINE.

SUBMARINE BOAT.

1,330,755.

Specification of Letters Patent. Patented Feb. 10, 1920.

Application filed April 13, 1918. Serial No. 228,367.

To all whom it may concern:

Be it known that I, PHILIP B. BRILL, a citizen of the United States, residing at Bridgeport, in the county of Fairfield and State of Connecticut, have invented certain new and useful Improvements in Submarine Boats, of which the following is a specification.

The invention has particular reference to 10 that class of submarine or submersible boats embodying a superstructure adapted to be rendered water-tight when the boat is operating upon the surface, and open to the surrounding body of water when the boat is 15 operating submerged, such as those as distinguished by the Lake type of boats. Heretofore in this type of boats, it has been the practice to arrange the valves controlling the inlet and outlet of water to and from 20 the space formed by and between the main hull and the superstructure of the boat through the sides of the superstructure. These valves are arranged to open outwardly, and hence form considerable 25 resistance when the boat is operating submerged, and in consequence, retard the speed of the boat.

The object of my invention is to avoid these objections, and hence to eliminate such 30 speed resisting surfaces.

The invention consists in arranging a channel or channels athwart-ships of the superstructure, and in providing perforated plates at the ends of the channels whereby 35 to throw the latter into open communication with the surrounding body of water when the boat is submerged, and in arranging valves in the walls of the channels for controlling the inlet and outlet of water to and 40 from the space formed by the superstructure, said valves being operable from within the main hull of the boat in substantially the same manner as that now employed for 45 operating the valves opening through the sides of the superstructure, it, of course, being understood that the perforations in the plates covering the ends of the channel or channels are of sufficient area to permit a sufficient quantity of water to have access 50 to the valve openings controlling the admission of the water to the superstructure space so that the superstructure space may be filled as rapidly as in the present arrangement of the side valves.

55 The invention comprises certain details of

construction and novel arrangement of parts as will be hereinafter fully described and then claimed.

In the drawings, illustrating the invention, in the several figures of which like parts are similarly designated, Figure 1 is a horizontal sectional plan view drawn through the forward end of the superstructure of a submarine or submersible boat embodying my improvements. Fig. 2 is a 65 transverse section of the same drawn on the line *a—a* of Fig. 1. Fig. 3 is a similar view showing a slightly modified construction of the invention. Fig. 4 is a detail longitudinal sectional view drawn on a 70 larger scale on the line *b—b* of Fig. 1.

1 designates the forward end of a submarine or submersible boat having a superstructure 2 arranged thereon which is adapted to be maintained normally water-tight 75 when the boat is operating upon the surface, such as those which are commonly known as the "Lake" type of submarine boats.

Heretofore it has been the practice, in water-tight superstructures, to provide 80 valves upon the sides of the substantially vertical walls of the superstructure for controlling the admission of water to the space or spaces within the superstructure. These valves, of necessity, open outwardly, as do 85 other valves of a submarine boat controlling the admission of water to the several compartments of the boat. Obviously, it is apparent that when a valve is arranged in the main hull, or in the superstructure, and de- 90 signed to be opened outwardly, that frictional surfaces are provided which tend to retard the speed of the boat when the latter is maneuvering below the surface of the water, and that such projections would be- 95 come easily entangled in anti-submarine nets or other defense means provided to obstruct the passage of submarines. My invention seeks to overcome these objections, as will be hereinafter fully explained. 100

The aforesaid superstructure 2 is provided at suitable points throughout the length of the boat with athwart-ships channelways 3 extending through the superstructure and having their ends covered by perforated plates 4 adapted for throwing the channelways into open communication with the surrounding body of water when the boat is submerged. The vertical walls 5 of the channelways 3 are provided with one or 110

more openings 6, which are surrounded by castings 7 providing valve seats for valves 8, the stems 8' of the valves being supported at their outer ends in bearings 9 preferably carried by the castings 7, and having their inner ends threaded through hubs of beveled gears 12 journaled in bearings 10 supported upon the main hull of the boat. The stems of the valves are provided with 10 keyways 11 to receive keys 11' formed on the bearings 10, to prevent the stems from rotating. Beveled gears 12 are threaded upon the stems 8', and the gears 12 are meshed with beveled gears 13 carried at the 15 upper end of shafts 14, provided with beveled gears 17 mounted in suitable bearings 18 supported within the vessel. The gears 17 are meshed by operating gears 19 carried at the outer end of shafts 20 each 20 having its inner end provided with a hand operated wheel 21, whereby, through the rotation of the shafts 20, the valves will be moved toward or away from their seats.

As is the prevailing practice, the super- 25 structures of submarine boats have their outer or substantially vertical walls connected to the hull at points below the extreme upper surface of the main hull, thereby forming pockets upon either side of the 30 space formed by and between the superstructure and the main hull, which necessarily prevents complete drainage of all waters collected therein when the said space is filled upon the submergence of the boat. 35 In order to avoid this objection, I purpose constructing the main hull of the boat, between the vertical walls of the transverse partitions 5, with depressions 22, and to locate the valves adjacent to the outer sides 40 of said transverse partitions, well down within the depressions 22, so that when the said valves are open, the entire contents of the superstructure will be drained outboard when the boat emerges.

45 I do not want to be limited to this construction, however, as it will be apparent, as shown in dotted lines in Fig. 3, that the lower corners, formed by and between the outer walls of the superstructure and the 50 main hull of the boat, may be filled in with cement or other suitable material, whereby to prevent the collection and retention of water, or I may employ auxiliary valve controlled openings 6' to release the water, 55 as shown in dotted lines in Fig. 3 of the drawings.

I have shown my invention as having three valves controlling the inlet to the several compartments of the superstructure 60 of a submarine boat, but it will, of course, be understood that I am not limiting myself to such details as it will be obvious to anyone skilled in the art to which the invention relates that one or more valves may be 65 employed as is necessary. This, however,

will be governed according to the capacity of the compartment to be filled or drained, and the time calculated in which to drain such compartments. While not shown, it will also be obvious that suitable gearing 70 may be formed between the wheels 21 and the gearing controlling the opening and closing of the valves 8, whereby each set of valves may be simultaneously operated through one operation of a single hand or 75 power controlled wheel 21.

It will be appreciated that while the perforations in the plates covering the ends of the athwart-ships channels will necessarily offer slight resistances, nevertheless, from 80 experiments, it has been proven that such obstructions are infinitesimal compared with the obstructions occasioned by the valves and their stems when arranged upon and projected beyond the sides of the boat. 85

Since the constructions of water-tight superstructures are well known in the art, applicant has not thought it necessary to show the hull of a boat in its entirety, nor that of the superstructure arranged upon 90 the boat, and, therefore, confines his illustration to only a portion of the forward end of a boat.

Applicant further desires it understood that any number of athwart-ships channels 95 may be employed throughout the length of the boat; and furthermore, that any specific details, other than those shown, may be employed for operating the valves for controlling the admission of water to the space or 100 spaces within the superstructure.

It will also be appreciated that stuffing-boxes 15 will be arranged around the shafts 14 to prevent ingress of water to the interior of the main hull of the boat, said stuffing-boxes being connected to the plating of the 105 main hull as shown in Fig. 4.

What I claim is:—

1. In a submarine boat, a normally water-tight superstructure built thereon, and having continuous athwart-ship channels open at each end to the surrounding body of water when the boat is submerged, and means for controlling the ingress and egress of water to and from the space or spaces 115 formed by and within the superstructure.

2. In a submarine boat, a normally water-tight superstructure built thereon, having continuous athwart-ship channels in open communication at each end with the surrounding body of water when the boat is submerged, the walls of said channels having openings communicating with the spaces formed by and between said superstructure and the main hull of the boat, and valves 120 controlling said openings.

3. In a submarine boat, a normally water-tight superstructure built thereon, having continuous athwart-ship channels in open communication at each end with the sur- 130

rounding body of water when the boat is submerged, the walls of said channels having openings communicating with the spaces formed by and between said superstructure 5 and the main hull of the boat, outwardly opening valves controlling said openings, and means for operating said valves from within the main hull of the boat.

4. In a submarine boat, having a normally water-tight superstructure built thereon, said superstructure having continuous athwart-ship channels in open communication at each end with the surrounding body of water when the boat is submerged, the 10 walls of said channels having openings com-

municating with the spaces formed by and between said superstructure and the main hull of the boat, outwardly opening valves controlling said openings, means for operating said valves from within the main hull of 20 the boat, and perforated plates covering the ends of said channels.

In testimony whereof I have hereunto set my hand this 9th day of April, A. D. 1918.

PHILIP B. BRILL.
